UNITED STATES PATENT OFFICE

100,173

DESIGN FOR AN AUTOMOBILE INSTRUMENT PANEL

Richard Mayer, New Rochelle, N. Y.

Application May 8, 1936, Serial No. 62,545

Term of patent 3½ years

To all whom it may concern:

Be it known that I, Richard Mayer, a citizen of the United States, residing at New Rochelle, in the county of Westchester and State of New York, have invented a new, original, and ornamental Design for an Automobile Instrument Panel, of which the following is a specification, reference being had to the accompanying drawing, forming part thereof.

The drawing is a perspective view of an automobile instrument panel showing my new design.

I claim:

The ornamental design for an automobile instrument panel, substantially as shown.

RICHARD MAYER.
